(57) **CLAIM**

The ornamental design for an orthopedic brace, as shown and described.

DESCRIPTION

FIG. 1 is a top perspective view of an embodiment of an orthopedic brace in accordance with the present invention. FIG. 2 is a bottom perspective view of the orthopedic brace of FIG. 1.

FIG. 3 is a bottom view of the orthopedic brace of FIG. 1. FIG. 4 is a top view of the orthopedic brace of FIG. 1.

FIG. 5 is a right side view of the orthopedic brace of FIG. 1.

FIG. 6 is a left side view of the orthopedic brace of FIG. 1.

FIG. 7 is a front side view of the orthopedic brace of FIG. 1; and,

FIG. 8 is a rear side view of the orthopedic brace of FIG. 1. The broken lines shown in FIGS. 1-8 illustrate portions of the orthopedic brace that form no part of the claimed design.
